CLAIM

The ornamental design for footwear, as shown and described.

DESCRIPTION

FIG. 1 is a perspective view of the footwear;
 FIG. 2 is a left side view thereof;
 FIG. 3 is a right side view thereof;
 FIG. 4 is a top view thereof;

FIG. 5 is a front view thereof;
 FIG. 6 is a rear view thereof; and,
 FIG. 7 is a bottom view thereof.

The broken lines in the figures indicate stitching and do form part of the claimed design.

1 Claim, 7 Drawing Sheets(56)
